UNITED STATES PATENT OFFICE.

FREDERICK T. FLINCHBAUGH, OF YORK, PENNSYLVANIA, ASSIGNOR TO JAMES M. TURNBULL, OF YORK, PENNSYLVANIA.

WASHING-MACHINE.

1,006,073.

Specification of Letters Patent. Patented Oct. 17, 1911.

Application filed September 22, 1910. Serial No. 583,229.

To all whom it may concern:

Be it known that I, FREDERICK T. FLINCHBAUGH, citizen of the United States, residing at York, in the county of York and State 5 of Pennsylvania, have invented certain new and useful Improvements in Washing-Machines, of which the following is a specification.

This invention has for its primary object 10 a washing machine of simple, durable and efficient construction, embodying an actuating shaft extending up from underneath the tub of the machine through the bottom thereof, the outer end of said shaft working 15 in a tubular casing and vertically disposed within the tub, and a washer element provided with a sleeve extending down into the casing and over and around the upper end of the shaft and having a free vertical movement 20 relative to the shaft, but compelled to turn therewith.

With this and other objects in view as will more fully appear as the description proceeds, the invention consists in certain 25 constructions, arrangements and combinations of the parts that I shall hereinafter fully describe and claim.

For a full understanding of the invention, reference is to be had to the following 30 description and accompanying drawings, in which:

Figure 1 is a side elevation of a washing machine constructed in accordance with my invention; Fig. 2 is a side view of the actuating mechanism of the device; Fig. 3 is a 35 vertical longitudinal section; Fig. 4 is a detail perspective view of the washing element; and, Fig. 5 illustrates in detail some 40 of the parts serving to connect the operating shaft with the washing element.

Corresponding and like parts are referred to in the following description and indicated in all the views of the drawings by the same reference characters.

45 My improved washing machine comprises a tub A mounted upon legs B, and a base bar C which latter forms the main support for the actuating parts of the mechanism. The actuating parts include a fly wheel 1 50 which may be provided with a handle, if desired, or which may be operated by a belt or in any other desired way, the fly wheel 1 being mounted upon a shaft 2 which is journalled in standards 3 rising from the 55 base C. The shaft 2 carries a spur pinion 4

which meshes with a gear wheel 5 secured on one end of a countershaft 6 journalled in the standards 3. The wheel 5 is a crank wheel and is connected by a pitman 7 to a segment 8, whereby to effect a back and forth or oscillating movement to the segment. The segment meshes with a pinion 9 secured to the lower end of a vertically disposed shaft 10, the lower end of which is journalled in a step bearing in the base C. 60 The shaft 10 passes upwardly through a bearing collar 11 which is formed with a plate 12 by which it is secured to the bottom 13 of the tub A, and a tubular casing 14 is secured within the tub A and rises from 65 the bottom 13, said casing being formed integral with the bearing 11 at the upper end of the latter. The shaft 10 is formed with a squared or otherwise noncircular upper end 10^a over which a correspondingly 70 formed sleeve 15 is adapted to fit, the sleeve being inserted down into the tubular casing 14. The sleeve 15 forms part of a cap-plate 16 and extends downwardly therefrom, said cap-plate being secured by screws or similar 75 fastening devices to the circular body portion 17 of the washing element. This latter also includes any desired number of downwardly extending arms 18 arranged to engage the clothes within the tub. Preferably, the cap plate 16 of the washing element has a knob or handle 19 secured to it so as to render easy the operation of removing and replacing the washing element. The 80 tub A is provided with a top or lid 20 and the latter is in turn provided with a dome 21 designed to accommodate the upper end 90 of the washing element at the upper limit of movement of the latter.

From the foregoing description in connection with the accompanying drawings, the 95 operation of my improved washing machine will be apparent.

In the practical use of the device, after 100 the clothes have been placed within the tub A, the washing element is slipped into place, as illustrated in Fig. 3, the sleeve 15 being loosely inserted in the casing 14 and engaging the squared upper end 10^a of the shaft 10. The vertical position of the washing 105 element is, of course, determined by the amount of clothes in the tub, as the engagement of the washing element with the drive shaft is a vertically adjustable one. By rotating the shaft 2, it is obvious that the seg- 110

ment 8 will be rocked back and forth and will therefore effect the oscillation of the shaft 10 and the washing element which it supports. As all of the actuating parts are 5 down below the tub A, it is obvious that they may be kept at all times in a proper running condition by the application of lubricant, without the danger of the oil coming in contact with the clothes.

10 Having thus described the invention, what is claimed as new is:

A washing machine, comprising an elevated tub, a bearing secured to the bottom of the tub and provided with a tubular casing 15 extending up from the bottom of the

tub within the latter, a shaft extending through said bearing and up into the casing and spaced from the interior wall of the casing, means for actuating said shaft, and a washer element provided with a sleeve extending down into the casing and over and around the upper end of the shaft and having a free vertical movement relative to the shaft, but compelled to turn therewith. 20

In testimony whereof I affix my signature 25 in presence of two witnesses.

FREDERICK T. FLINCHBAUGH. [L. S.]
